E. SHERMAN.

FOOT REST.

APPLICATION FILED AUG. 31, 1905.

UNITED STATES PATENT OFFICE.

EMIL SHERMAN, OF CHICAGO, ILLINOIS.

FOOT-REST.

No. 815,046.

Specification of Letters Patent.

Patented March 13, 1906.

Application filed August 31, 1905. Serial No. 276,584.

To all whom it may concern:

Be it known that I, EMIL SHERMAN, a citizen of the United States, residing at Chicago, in the county of Cook and State of Illinois, have invented new and useful Improvements in Foot-Rests, of which the following is a specification.

This invention relates to a simple and inexpensive device which affords a portable and adjustable foot-rest adapted to be used in connection with easy-chairs, rockers, barber-chairs, and the like, and it is illustrated in the accompanying drawings.

Figure 1 is a perspective view of the device. Fig. 2 is an end view of the same.

In the drawings, 10 refers to a box-like receptacle adapted to hold newspapers or slippers, for instance. The ends of this box are segmental or curved in shape, as shown at 11, and 11^a represents a series of pin-holes in the upper edge of said end, adapted to receive pins 11^b for limiting or adjusting the movement of the foot-rest. The pins limit the swing of the foot-rest, or by setting them close together it will be held fixed. Two pivoted arms 15 are attached to the ends of the box, and between these arms is a cross-piece 13, which strikes the stop-pins. Mounted upon the arms 15 and forming upper sections thereof are two arms 12, having slots 14 and thumb-

screws 14^a, which clamp said sections and regulate the height of the foot-rest. At the top of the arms 12 is a pivoted foot-board 16, having a cushion 16^a, which provides a foot-rest. The foot-rest may be moved into different positions, and the extent of its movement can be adjusted by the pins 11^b. The height can be adjusted by the slot and thumb-screw connection.

The device is especially useful for supporting the feet and legs of a person sitting in a rocking-chair, in which case the foot-rest will swing back and forth as the person is rocking, thus accommodating itself to the movement of the rocker.

What I claim as new, and desire to secure by Letters Patent, is—

A foot-rest comprising a base-box having a series of holes in its ends and stop-pins in said holes, extensible arms pivoted to said ends and having a cross-piece arranged to strike against said stops, and a pivoted foot-board carried between said arms.

In testimony whereof I have signed my name to this specification in the presence of two subscribing witnesses.

EMIL SHERMAN.

Witnesses:
